BATTERY TERMINAL CLAMP

Samuel E. Carlson, Alhambra, Calif.

Application February 26, 1930. Serial No. 431,474

6 Claims. (Cl. 173—259)

My invention is an improved type of terminal clamp useful in establishing electrical connection between a cable or other suitable electrical conductor, and a terminal post of a storage battery.

An object of the invention is to provide a terminal clamp in which means are provided for tightening the clamp into physical and electrical engagement with a terminal post or equivalent structure, and in which the tightening means are disposed at a relatively remote point from the terminal post, thereby removing the tightening means from that locality in which corrosion occurs during normal use of a storage battery.

15 A further object is to provide a terminal clamp in which the tightening means are movable after having been tightened thereby, making it possible to first secure the clamp in operative position and subsequently move the tightening means to a position wherein it does not project from the battery. Similarly, when it is desired to remove the clamp, the tightening means may be swung from retracted position into a position wherein access to the tightening means is more convenient.

25 Another object is to provide a terminal clamp of the general character described, which is exceedingly simple in construction, being composed of relatively few and simple parts, and hence which is relatively inexpensive to manufacture.

30 In spite of this economical construction however, the clamp is fully capable of operating with a high degree of efficiency in securely maintaining physical and electrical engagement between the electrical conductor and the terminal post.

35 A still further object is to provide a terminal clamp adapted to be tightened through the expedient of a pair of opposed levers movable about a fulcrum which is adjustable to permit proper installation of the levers in conjunction with terminal posts of various sizes.

40 The invention possesses other objects and advantageous features, some of which, with those enumerated, will be set forth in the following description of the invention's particular embodiment which is illustrated in the drawing accompanying and forming a part of the specification.

45 Referring to the drawing:

Figure 1 is a perspective view of a portion of a storage battery showing one of my terminal clamps operatively installed thereupon.

50 Fig. 2 is a top plan view with portions of the figure broken away.

55 Fig. 3 is a side elevation of the clamp. This view may be considered as a vertical sectional view taken upon the line 3—3 of Fig. 2, with the direction of view as indicated. The dashed lines indicate the position into which the tightening means may be swung to facilitate tightening or loosening the clamp.

60 Fig. 4 is an enlarged vertical, transverse sec-

tional view taken upon the line 4—4 of Fig. 2, with the direction of view as indicated.

In terms of broad inclusion, the device of the present invention comprises a member to which an electrical conductor is permanently attached as by soldering or welding—this member having means engageable with a terminal post such as that commonly employed upon a storage battery. Tightening means are associated with the member in such a manner that it may be securely tightened upon the post, and this tightening means is of such a nature that the element thereof which is movable to effect tightening, is disposed at a relatively remote position from the terminal post. Furthermore, the tightening means are movable in respect to the post-engaging member, so that it may be swung to or from retracted position even when tightened, and thus permit manipulation of the tightening means when in a more accessible position than when retracted.

75 Whereas the device of the present invention is capable of establishing physical and electrical contact between a conductor and substantially any type of terminal post, it is herein shown and described as being particularly adapted for use in conjunction with a terminal post 6 of the type commonly employed upon a storage battery 7. A clamp used in such service must be especially efficient, because of the fact that one of the most common uses for a storage battery is upon vehicles such as automobiles, wherein it is subjected to severe shocks and vibration tending to loosen the engagement between the clamp and the post 6, with a consequent tendency to establish an inefficient electrical joint therebetween. Furthermore, such use of a storage battery results in an accumulation of grease and dirt upon the terminal posts and clamps associated therewith, which not only have a tendency to decrease the efficiency of the electrical connection therebetween, but also to make it difficult to tighten the clamp upon the terminal post, and to remove it therefrom. It is with these circumstances of use of a storage battery terminal clamp in mind, that the device of the present invention has been developed in an effort to obviate such undesirable conditions.

100 In my improved terminal clamp, the element which engages the terminal post 6, is in the form of a substantially U-shaped clamping member 8 comprising spaced arms 9 and 11, joined at one end by the same metal 12 which units the arms 9 and 11 to a socket member 13 within which an end of an electrical cable 14 may be securely attached. It is intended that the cable 14 be permanently attached within the socket member 13, by any means conducive to the development of the most efficient electrical connection. Hence

soldering or welding is most conveniently employed for this purpose.

The inner faces of the arms 9 and 11 adjacent their bases, are rounded to define a substantially cylindrical socket 16. The outer ends 17 and 18 of the arms 9 and 11 are spaced slightly from each other however, when the arms 9 and 11 are tightened against the post 6, the purpose being to cause pressure exerted against the outer faces 10 of the arms 9 and 11 at their outer ends, to increase the tightness of the engagement of the clamping member 8 upon the post 6. Aligned holes 21 and 22 are formed transversely of the outer ends 17 and 18 respectively, of the arms 15 9 and 11.

The structure thus far described, is the conventional terminal post clamp now universally employed, and my invention lies not in the construction of this element, but in the tightening 20 means hereinafter to be described, and in the adaptation of my improved tightening means to the post clamp.

This tightening means takes the form of a pair of opposed levers 26 and 27 preferably similar in construction. Each lever is preferably channel-shaped in cross-sectional configuration, having a bottom web 28 and side flanges 29. However, inasmuch as in the present modification, the tightening force for the levers 26 and 27, is applied thereto intermediate their ends, I prefer to form the flanges 29 considerably higher at the center of each lever than at the ends thereof, thus increasing the cross-sectional area of each lever, and consequently, the rigidity thereof, at the point of greatest bending moment.

A slight projection 31 is formed on the inner face of each lever 26, 27, adjacent the inner end thereof. These projections 31 are receivable within the holes 17 and 18 of the arms 9 and 11, with the result that these holes serve as sockets within which the projections 31 may be received to pivotally support the levers 26 and 27 upon the arms 9 and 11 respectively, for pivotal movement about a common axis normal to the engaging faces of the levers and arms. The projections 31 may be constructed most easily by pressing a portion of the metal of which the levers are constructed, outwards from the web 28 of each lever 26, 27, adjacent the inner end thereof.

An adjustable fulcrum is interposed between the outer ends of the levers 26 and 27. In its preferred form, this fulcrum is in the form of a bolt 32 extending through aligned holes 33 in the webs 28 of the levers 26 and 27 adjacent the outer ends thereof. A pair of nuts 34 and 36 are threaded upon the bolt 32, each of these nuts being positioned to engage the inner face of one of the levers 26, 27. Obviously, therefore, the effective spacing between the outer ends of the levers, may be varied by altering the position of one or both of the nuts 34, 36, upon the bolt 32.

A tightening bolt 37 extends through aligned holes 38 in the webs 28 of the levers 26 and 27 between the fulcrum bolt 32 and the projections 31. Preferably the bolt 37 is a carriage bolt having a non-circular portion 39 immediately under the head 41 thereof, this non-circular portion being fitted between the flanges 29 of one of the levers 26, so as to prevent the bolt from turning when the nut 42 which is threaded thereupon, is turned. The nut 42 is disposed upon the opposite side of the other lever 27 from that which is engaged by the head 41, so that when the nut 42 is tightened, the inner ends of the levers 26 and 27, i. e., the ends which engage the arms 9

and 11, will be forced together. I also preferably employ a washer 43 interposed between the nut 42 and the proximal lever 27.

The tightening means formed by the levers 26 and 27 and the associated bolts 32 and 37, may be used to supplant the ordinary bolt which is commonly passed through the aligned holes 21 and 22 in the ends of the arms 9 and 11 of the conventional terminal clamp. After this conventional bolt has been removed from the holes 21 and 22, the levers 26 and 27 should be mounted upon the arms with the projections 31 seated within the holes 21 and 22. The device should then be positioned upon the terminal post 6 with which it is desired to establish electrical connection to the cable 14 which previously has been secured within the socket member 13. This is done by slipping the arms 9 and 11 downwards over the terminal post 6, to seat the terminal post within the socket 16—it being understood that the nut 42 is sufficiently loose to permit of so doing. The nut 42 may then easily be tightened with the levers 26 and 27 extending vertically from the top of the battery 7, which, of course, disposes the nut 42 in a more convenient position 100 to permit engagement thereupon, of a wrench. Inasmuch as the bolt 37 is disposed between the fulcrum bolt 32 and those ends of the levers which engage the arms 9 and 11, this tightening of the nut 42 upon the bolt 37, will result in pressing the 105 arms 9 and 11 tightly against the post 6, to prevent inadvertent displacement thereof through vibration, and to insure an efficient electrical connection between the post 6 and the cable 14.

After the nut 42 has been tightened in this 110 manner, the tightening means may be swung downwards about the axis of the holes 21 and 22, to position them parallel with and closely adjacent the upper surfaces of the battery 7. Obviously, in this position they do not project above 115 the battery beyond the upper end of the post 6, with the result that they do not occupy any space which should be preserved for other elements.

It should be observed that the bolt 37 and the nut 42 are spaced at a more remote position from 120 the terminal post 6, from that occupied by a bolt which extends through the holes 21 and 22 in the conventional manner. It is well known that during the customary use of a storage battery, corrosion develops at the terminal posts, and more 125 particularly at the positive terminal post. However, by positioning the bolt 37 and its nut 42 more remotely from the terminal post, removal of the terminal clamp from the post is facilitated because of the fact that the bolt 37 and nut 42 are positioned outside that locality at which the corrosion develops.

The adjustability of the fulcrum bolt 32 permits of installation of the tightening means upon 130 clamping members 8 of various sizes. The nuts 34 and 36 should be so positioned upon the fulcrum bolt 32 that the levers 26, 27, are disposed in substantially parallel arrangement when the clamp is tightened, thus securing the firmest engagement of the levers 26 and 27 upon the arms 140 9 and 11.

It should also be observed that the clamp may be tightened by first setting the nut 42 in proper position upon the bolt 37, and then adjusting the nut 34 and/or 36 so as to increase the distance therebetween, and force the outer ends of the levers 26 and 27 apart. When so used, the levers are of the first class, inasmuch as the bolt 37 which acts as the fulcrum, is positioned between 145 the work and the point of application of the force.

Under certain circumstances, this manner of using the device may offer greater convenience because of the greater distance of the nuts 34 and 36 from any surfaces which might interfere with the manipulation of a wrench.

It is to be understood that the details of the invention as herein disclosed, are subject to alteration within the spirit or scope of the appended claims.

10 I claim:

1. A terminal clamp comprising a pair of arms having a passage therebetween adapted to receive the terminal to be clamped, a pair of levers engaging said arms, and means for forcing said levers toward each other to clamp said arms upon said terminal, said levers being pivotally engaged with said arms to dispose said forcing means optionally in a plurality of positions.

2. A terminal clamp comprising a pair of arms embracing a terminal post, a lever associated with each of said arms, one end of each lever being pivotally joined to the associated arm for rotary movement about an axis normal to the engaging faces of said arm and lever, a fulcrum interposed between said levers, and means for forcing said levers toward each other.

3. A terminal clamp comprising a pair of arms embracing a terminal post, a lever associated with each of said arms, one end of each lever being pivotally joined to the associated arm for rotary movement about an axis normal to the engaging faces of said arm and lever, a fulcrum interposed between said levers adjacent the other ends thereof, a bolt extending through both levers between said fulcrum and said arms, and means for tightening said bolt.

4. A terminal clamp comprising a pair of arms embracing a terminal post, each arm having a socket in the outer face thereof, a lever associated with each of said arms, each of said levers having a projection on its inner face receivable within the associated socket, a fulcrum interposed between said levers, and means for forcing those portions of the levers engaging the arms toward each other.

5. A terminal clamp comprising a pair of arms having a passage therebetween adapted to receive the terminal to be clamped, a pair of levers engaging said arms, at least one of said levers being of channel-shaped cross section with its flanges extending from its web in a direction away from the other lever, a bolt passing through both levers and having a non-circular portion disposed between said flanges to hold said bolt from turning, and a nut threaded upon said bolt beyond said other lever.

6. A terminal clamp comprising a pair of arms having a passage therebetween adapted to receive the terminal to be clamped, a pair of levers engaging said arms, at least one of said levers being of channel-shaped cross section with its flanges extending from its web in a direction away from the other lever, a bolt passing through both levers and having a non-circular portion disposed between said flanges to hold said bolt from turning, and a nut threaded upon said bolt beyond said other lever, said levers being pivotally engaged with said arms to dispose said nut optionally in accessible position or in retracted position.
